(57) **CLAIM**

The ornamental design for a dispenser for multiple web rolls, as shown and described.

DESCRIPTION

FIG. 1 is a perspective view of a dispenser for multiple web rolls including label rolls, showing our new design;

FIG. 2 is a front elevational view of the dispenser;

FIG. 3 is a rear elevational view of the dispenser;

FIG. 4 is a top plan view of the dispenser;

FIG. 5 is a bottom plan view of the dispenser;

FIG. 6 is a right side elevational view of the dispenser; and,

FIG. 7 is a left side elevational view of the dispenser.

The dispenser may be either transparent or translucent. The outer shape of the dispenser is within the scope of the claim.

1 Claim, 6 Drawing Sheets
